MUSICAL INSTRUMENT

Filed Feb. 3, 1927

Inventor:

Wilhelm Blaauw

UNITED STATES PATENT OFFICE

WILHELM BLANK, OF PLAUE, GERMANY

MUSICAL INSTRUMENT

Application filed February 3, 1927, Serial No. 165,586, and in Germany February 11, 1926.

This invention relates to musical instruments, particularly to electric pianos of that kind well known in art in which the sounds or tones are produced by electric currents flowing in circuits closed by keys or an automatically operating device. In order to produce an oscillation of the electric currents coming from any source, such as a galvanic battery or an accumulator or the like, said oscillations being shaped in a sinelike manner, I use a microphone filled with coal grit or any other microphone capable of changing mechanical oscillations of any parts in corresponding variations of electric currents. To the membrane of said microphones a bridge or cone or any other connecting means is attached, the free end of which touches any oscillatory part, f. i. a string, a plate spring fastened on one end of it or a tuning fork. The oscillations of these parts are produced by appertaining electro-magnets influenced by currents controlled by said microphones.

In order that the principle thereof may be readily understood I have disposed a single embodiment thereof by way of example in the accompanying drawing, wherein

Fig. 1 shows a vertical section through a piano embodying the invention,

Fig. 2 illustrates the electrical connection of the operating parts of the piano shown in Fig. 1, and

Fig. 3 is a detail showing the position of an oscillatory string relative to its electro-magnet.

A string 1 is stretched between the fastening points 2 and 3 in any manner well known in art so that the celerity of the oscillations of the string and the height of the tone produced by it can be regulated.

The electro-magnet 4 is arranged in relation to the string 1 in such a manner, that the string can move freely between the poles 5 of the magnet 4 tapered one to the other. In this way the string is drawn by weak currents to the narrowest points between the poles.

The oscillations of the string 1 are transferred to the membrane or diaphragm 7 of the microphone by a bridge or cone or any other connecting piece 6 weakly pressed

against the string 1 by the microphone. This is removably attached by screws 71 to a lever 72 one end of which is hinged to a road 73 supported by the casing of the piano, whilst the other end of said lever 72 is adjustably held by a screw 74 arranged in a road 75 also mounted in the casing of the piano. Between the membrane 7 and the counter-plate 8 of the microphone coal grit is filled in.

In order to influence the magnet 4 in accordance with the oscillations of the string 1, a wire *a* is running from the electric source 9 to the collecting wire *b* which is one part of a contact or switch embodied by a key, or an automatically working roller, or any other appliance well known in art and actuated in any way, for instance by depressing a key supporting the other part 10 of the contact or switch. From here a wire *c* runs to the microphone plate 8. The electric currents then pass through the coal-grit to the membrane 7 and then through the wire *d*, the coil 14 of the magnet 4 and the wire *e* to the collecting wire *f*, which is electrically connected with the switching arm 20 of a resistance controller. This arm 20 is moved by a pedal 21, connected with the side-arm 22 of the switching arm 20 by a rod 23, overcoming the power of the spring 24 seized on another side-arm 25 of said switching arm 20. The electric currents flow through this arm 20 to a resistance coil or a row of resistances 26. One end of this coil or row is connected by means of the wire *g* to the other pole of said battery 9. The other end of the resistance 26 is connected to a telephone or loud-speaker or the like 12 by the wire *h* in order to make audible the electric currents, then flowing through the wires *k* and *g* also to the battery 9. The currents coming from the wire *f* are divided in accordance to the position of the switching arm 20, one part of them passing through the telephone 12 to the battery 9 and the other immediately that way. By shifting the switching arm 20 the intensity of the tones is controlled.

Between the collecting wires *b* and *f* any number of wires *c'*—*e'*, *c''*—*e''*, *c'''*—*e'''*... can be arranged, each of them having a switch 10, a microphone 7, 8 and a magnet coil 14. 100

- The different oscillating parts 1 belonging to those wires produce different tones. By closing the switches 10 tones are composed. The electric current passing through these switches is influencing the respective magnets 4 pulling the oscillating parts away from the microphones and enlarging the resistance of this latter, till the current is reduced so far that the magnet 4 cannot hold the oscillating part 1. Then this swings back over the original position, thus reducing the resistance of the microphone. The current then growing again influences the magnet 4 in such a manner that it can draw again the oscillating part. This operation and procedure is repeated in accordance with the oscillatory peculiarities of the oscillating part 1. In this manner the current coming from the electric source 9 is altered into a sinelike changing current capable of producing a tone like that of a violin made audible either immediately by the oscillating part with the help of resonators or by telephones, loudspeakers or the like.
- The arrangement above described can be altered in great variety. Instead of a string of steel-band—fastened on both ends—, or a plate or bar spring 1'—fastened on one end of it only—, or a tuning fork 1, or a membrane, or a plate attached on one edge to a spring can be used as an oscillating part. Different kinds of such parts can be arranged in one musical instrument, for instance tuning forks for the lower tones and strings for the higher tones, but each of these oscillating parts is tuned for a determinate and appointed tone. Therefore strings are stretched in a distinct measure and plate springs are fastened on their support in such a way that the lengths of their free swinging parts can be varied. Or in all these cases a bridge 15 can be arranged movably for influencing the oscillations of the parts. For this purpose the microphone 7, 8 with its bridgelike cone 6 can be used by arranging it near the fastened end of the oscillating part indicated in the drawing by the bridge 15.
- If the weak currents controlled by the microphone cannot influence the electro-magnets or a loud speaker in sufficient manner, they are to be reinforced in a well known manner.
- The principle of my invention consists in using microphones capable of changing the variations of mechanical pressure produced by oscillating parts into corresponding variations of electric currents for said purpose, whereby one part of said microphones, for instance their casing, is removably supported by the casing of the musical instrument.
- Having thus described one illustration and embodiment of my invention, I desire it to be understood that although specific terms are employed, they are used in a generic and descriptive sense and not for purposes of limitation. Changes and variations may be

made in the construction by which the invention claimed is carried into effect without departing from the spirit or scope of the invention.

Having thus described the invention, what I claim as new is:—

1. A musical instrument having oscillating parts influenced by electro-magnets and influencing mechanically microphones capable of changing the variations of mechanical pressure of said oscillating parts into corresponding variations of electric currents flowing through said microphones, said microphones removably supported by the casing of the musical instrument.

2. A musical instrument having in combination of oscillating parts, electro-magnets influencing said oscillating parts, an electric source, wires connected to said source and forming circuits for influencing said electro-magnets and switches for closing said circuits, with microphones mechanically connected to said oscillating parts and capable of changing the variations of mechanical pressure of said oscillating parts into corresponding variations of electric currents flowing in said circuits and influencing said electro-magnets, said microphones removably supported by the casing of the musical instrument.

3. A musical instrument having in combination of oscillating parts, electro-magnets influencing said oscillating parts, an electric source, wires connected to said source and said electro-magnet by forming circuits and switches for closing said circuits, with microphones removably connected to said oscillating parts by connecting means capable of transferring the oscillations of said oscillating parts into movements of the membrane of said microphones capable of changing the variations of mechanical pressure of said oscillating parts into corresponding variations of electric currents flowing in said circuits and influencing said electro-magnets, said microphones removably supported by the casing of the musical instrument.

4. A musical instrument having in combination of oscillating parts, electro-magnets influencing said oscillating parts, an electric source, wires connected to said source and to the coils of said electro-magnets by forming circuits and switches for closing said circuits, with microphones removably connected to said oscillating parts by connecting means capable of transferring the oscillations of said oscillating parts into corresponding movements of the membrane of said microphones capable of changing the variations of mechanical pressure of said oscillating parts into corresponding variations of electric currents flowing in said circuits and influencing said electro-magnets and with a removable resistance device for dividing the currents flowing through said circuits one part of said

currents going to a device for making it audible.

5. A musical instrument having in combination of strings, electro-magnets influencing said strings and embracing them by poles tapered or inclined one relative to the other, an electric source, wires connected to said source and the coils of said electro-magnets by forming circuits and switches for closing 10 said circuits, with microphones connected to said strings by connecting means capable of transferring the oscillations of said strings into corresponding movements of the membrane of said microphones capable of changing the variations of mechanical pressure of 15 said strings into corresponding variations of electric currents flowing in said circuits and influencing said electro-magnets and with a removable resistance device for dividing the 20 currents flowing in said circuits one part of said currents going to a device for making it audible, said microphones removably supported by the casing of the musical instrument.

25 In witness whereof I affix my signature.
